UNITED STATES PATENT OFFICE.

JOSEPH S. FIELD, OF BROOKLYN, NEW YORK.

DESIGN FOR SHEET-METAL BOXES.

Specification forming part of Design No. **11,158**, dated April 15, 1879; application filed March 14, 1879.
[Term of patent 3½ years.]

To all whom it may concern:

Be it known that I, JOSEPH S. FIELD, of Brooklyn, in the county of Kings and State of New York, have invented a new and Improved Design for Sheet-Metal Boxes; and the following is declared to be an exact description of the same.

This design relates to the shape and configuration of the sheet-metal box.

Heretofore cash-boxes and other boxes of sheet metal have been cubical or oblong, with the sides parallel. There is nothing ornamental in the shape of these boxes.

My present design is for improving the appearance of sheet-metal boxes; and consists in the configuration substantially as shown in the elevation, Figure 1, of accompanying drawings, and end view, Fig. 2.

The top *a* and bottom *b* of the box are flat, or nearly so. The sides *c* and ends *d* of the box are inclined, so that they are nearer to-

gether at the upper edges than at the bottom, and hence are similar to a truncated pyramid. The sides *c* and ends *d* of the cover are inclined in the opposite direction, so that the top and bottom of the box are larger than the joint between the cover and the bottom of the box. This produces a handsome appearance in the box, and renders it more acceptable and ornamental.

I claim as my invention—

The ornamental shape and configuration of the sheet-metal box, the same having the sides and ends of the lower part of the box inclined inwardly, and the sides and ends of the lid of the box also being inclined inwardly, as shown.

Signed by me this 12th day of March, A. D. 1879.

JOSEPH S. FIELD.
